ABSTRACT OF THE DISCLOSURE

Subterranean communication paths are established between wells communicating with a common oil-bearing strata by injecting into one well steam at a temperature and pressure sufficient to crack the crude within the strata and form hydrogen and thereafter detecting the presence of this hydrogen within another well in this oil-bearing strata.

This invention relates to a method for tracing the subterranean communication paths between producing wells. In one of its aspects, it relates to a method for tracing subterranean passageways by forming hydrogen in situ at a first well and analyzing the production of a second well for hydrogen. In another of its aspects, the invention relates to a method for determining the communication between a plurality of wells by injecting into a first well a quantity of steam at a temperature and pressure sufficient to crack hydrocarbons therein, and analyzing the fluid produced at a producing well in the vicinity of said first well to detect the presence of hydrogen.

Modern oil field practice dictates in certain circumstances that various tracts of producing wells be pooled in order to recover the maximum amount of hydrocarbons from the oil bearing strata. In the unitizing or pooling operation, it is common practice to use one of the producing wells as an input well and other producing wells located around the input well as producing wells. In one operation, for example, fluid is injected into the input well, and the fluid is used to drive the hydrocarbons toward the producing wells. In another operation, for example, combustion is initiated in the producing strata, and the pressure which builds up from such combustion will drive hydrocarbons toward the producing wells.

It is obvious from the above examples that it is a necessary prerequisite to any secondary recovery operation in which an input and an output well is used to know which wells have communicating passages therebetween. In some cases, one producing well will be producing hydrocarbons from a particular strata, whereas a second producing well will be producing hydrocarbons from a second producing strata. In such a case, although the producing wells could possibly be in communication, they will not be considered to be in communication for secondary recovery purposes.

In other instances, a fault will disrupt communication between two producing wells which are producing from the same strata. In most instances, it cannot be determined from mere inspection of the depth of the well or the type of fluid which is produced from the well whether or not various wells have communicating paths therebetween.

A number of methods have been devised to determine whether a series of producing wells have a communicating passage therebetween. One of such methods contemplates injecting a boron-containing compound, such as borax, into an input well in a water flood operation. Thereafter, the production from the various producing wells is tested for the presence of boron. In such a manner the flow of water can be traced from input wells to output wells. However, as is obvious from the above discussion, this process is limited to a water flood operation.

Another prior art method contemplates introducing a

2

radioactive gas, such as Radon, into a reservoir through a first well and detecting the radioactivity of the strata by positioning in other wells radioactivity detection devices. This method requires expensive equipment for producing and analyzing the radioactivity within the well bore. Further, radioactive material can be dangerous and must be specially handled.

Still another prior art method contemplates tracing the communicating paths between well bores in a pressurizing operation. In such an operation, non-condensable gases, such as CO, H₂, NO, and N₂, are injected into an input well with repressurizing gas, normally principally CH₄. The non-condensable gas is then detected at the producing well. CO, NO, and N₂ can be easily detected, but the operation, for the most part, is limited to the repressurizing type of operation. Further, hydrogen is sometimes present in the repressurizing gas and the reservoir gas. Thus, if hydrogen were added to the repressurizing gas, and detected in a producing well, it would not be clear whether the hydrogen came from the reservoir gas or from the input well.

I have found a simple, inexpensive method for tracing subterranean communication paths by forming hydrogen in situ and thereafter detecting hydrogen from the producing wells. I have found that this operation can be accomplished during a special type of secondary recovery operation in a viscous crude reservoir.

By various aspects of this invention, one or more of the following, or other, objects can be obtained.

30 It is an object of this invention to provide a method for tracing the flow of fluids through underground oil producing strata.

35 It is a further object of this invention to provide a simple, inexpensive method for determining subterranean communication between various producing wells.

35 It is a still further object of this invention to provide a simple method for determining the subterranean communication between an input well and a series of output wells.

40 It is a still further object of this invention to provide a method for tracing subterranean communication paths while simultaneously carrying out a secondary recovery process.

45 Other aspects, objects, and the several advantages of this invention are apparent to one skilled in the art from a study of this disclosure, the drawing, and the appended claims.

According to the invention, subterranean communication paths can be traced by producing hydrogen in situ 50 in a first well, and thereafter detecting the presence of hydrogen in the production of a second well within the general area of the first well. Hydrogen has been found to be a most effective tracing agent, since it has a high diffusion rate through porous media. The fast diffusion rate of hydrogen provides a rather fast, efficient method 55 for tracing the subterranean communication paths.

In one embodiment of the invention, steam can be introduced into a first well at a temperature and pressure sufficient to crack the crude around the well bore in situ.

60 The invention contemplates injecting high pressure steam into the oil bearing formation, at a temperature in excess of 600° F., high enough to induce in situ hydro-cracking of the crude, thereby producing hydrogen which, under the pressure of the steam being injected, is forced 65 at a high rate through the pathways of the formation to the other wells drilled into the formation and communicating with the injection well. After starting the injection, the effluent of the peripheral wells is continuously monitored for hydrogen production by conventional detectors. 70 After a short period of time (5–20 days), the injection well can be shut-in, and monitoring can be continued for some time to provide additional hydrogen diffusion data.

From the time needed for hydrogen evolution and the normalized comparative quantity of hydrogen produced from the peripheral wells, a communication path pattern can be established. If a well fails to produce hydrogen at the end of the test period, it may be assumed that a barrier exists to free communication and/or that the well is producing from a different or faulted horizon.

The invention can be further exemplified by reference to the accompanying figure, which shows an embodiment of the invention.

Referring now to the figure, an input well 1 communicates with oil bearing strata 6 and 6'. Wells 2, 3, and 4 also communicate with oil bearing strata 6 and 6' and are adapted to produce oil therefrom. Fault line 5 disrupts communication between oil bearing strata 6 and 6'. In operation, steam is injected into well 1 and cracks the crude in zone 7 of oil bearing strata 6. Because output wells 2 and 3 communicate with input well 1, the hydrogen produced in situ in the cracked oil zone 7 will be detected in the production from wells 2 and 3. However, no hydrogen will be detected from well 4 because communication between well 1 and well 4 are blocked by fault line 5.

The invention can be carried out simultaneously during a secondary recovery process which uses steam in an input well. In copending application Ser. No. 422,833, filed Dec. 31, 1964, there is disclosed and claimed a method for the secondary recovery of a viscous crude by injecting into a producing well steam at such a temperature and pressure to cause cracking of the crude, shutting in the well for a soaking period, and then producing the well. A single well or a plurality of wells can be operated according to this invention. In such an operation, it would be possible to simultaneously detect hydrogen from the producing wells. During the steam injection period and during the soaking period, the production from nearby producing wells can be tested for hydrogen production. Preferably, the adjacent producing wells would not have had steam injected thereto a reasonable time prior to the testing for hydrogen.

As is obvious from the above description, this method is especially applicable to formations of highly viscous crudes in which the tracing of pathways is particularly difficult, especially by injection of fluids and chemicals. Further, therefore expensive chemical treatment and pumping can be avoided by the in situ generation of hydrogen by the steam cracking.

The following is a specific example of the successful operation of the invention in the Oficina Sands of Eastern Venezuela.

Example I

Steam injection into a well was terminated after 20 days of continuous steam injection. A total of 5.58 billion B.t.u. was injected, corresponding to about 15,200 barrels of water at reservoir conditions. At no time during this injection period was there any evidence of a build-up of resistance to flow. Monitoring of offset wells showed that hydrogen broke through at three of the wells, but not at a fourth offset well. None of these wells showed production increases. Free hydrogen was detected in producing wells at a distance of about 700 feet from the steam injection well only about ten days after steam injection began.

The above example shows that the injection of steam into an oil bearing strata at a temperature and pressure sufficient to crack the crude therein and the monitoring of hydrogen at nearby wells is rapid, efficient, and effective method for tracing the subterranean communication paths of oil bearing strata.

The following example shows how the invention can be combined with a steam injection secondary recovery operation.

Example II

This high pressure steam cracking or hydro-cracking process was successfully operated in the Oficina Sands of

Morichal Field of Venezuela. In-situ cracking took place:

(1) Initial production of 5.3° API oil from a reservoir in which the native oil was approximately 14° API gravity after a 30 day 640° F. steam injection period, followed by a 5 day soak period. The gravity gradually increased with time, finally exceeding the original API gravity as the lighter ends produced. Production was increased several times.

(2) The characteristic sulfurous odor of cracked oil was detected in the vicinity of the oil after steam injection indicating that the process operated successfully.

(3) Free hydrogen was detected in the produced stream of oil produced from nearby wells communicating with the injection well.

The advantages of high temperature steam cracking of oil in place are: no combustion, no destruction of oil by burning, increased recovery of oil in place, less danger of well fires, and improved recovery of highly viscous crudes.

The above example shows that the free hydrogen, detected in the produced stream of oil produced from nearby wells, indicates the communication of the injection well with the producing well simultaneously while carrying out the secondary recovery operation.

It is obvious that in carrying out the invention, where the producing strata sought to be tested is low in hydrogen producing materials, the injection fluid can also contain small amounts of hydrogen to supplement hydrogen formed therein.

Reasonable variation and modification are possible within the scope of the foregoing disclosure, the drawing and the appended claims to the invention, the essence of which is that subterranean communication paths can be traced by forming hydrogen in situ in a first well and testing the production of a second well for hydrogen.

I claim:

1. A method for tracing subterranean communication paths between an input well and an output well in communication with oil-bearing strata containing high viscosity crude, in which the strata communication between existing wells has not been established, said method comprising injecting into said input well steam at a temperature and pressure sufficient to crack the crude therein, thereby forming hydrogen in the cracking process, and thereafter detecting hydrogen from said output well in the vicinity of said input well.

2. A method according to claim 1 wherein the temperature of said steam is at least 600° F.

3. A method for detecting a flow path between a first well and a second well communicating with oil-bearing strata containing viscous crude while simultaneously recovering hydrogen from said strata in which communication between existing well walls has not been established, said method comprising injecting into said first well steam at a temperature and pressure sufficient to crack the crude in said strata, shutting said first well in for a soaking period, and producing said first well, and simultaneously during said steam injection, said shutting in period, and said producing period, detecting hydrogen at said second well, said second well not having had steam injected therein a reasonable time prior to the detecting period.

4. A method according to claim 3 wherein said second well is a producing well.
